CLAIM

The ornamental design for a pet grooming station, as shown and described.

DESCRIPTION

FIG. 1 is a top, perspective view of the pet grooming station; the view showing my new design;
FIG. 2 is a top, perspective view thereof;
FIG. 3 is a top, perspective view thereof;
FIG. 4 is a top, perspective view thereof;
FIG. 5 is a bottom, perspective thereof;
FIG. 6 is a bottom, perspective thereof;
FIG. 7 is a front elevation view thereof;
FIG. 8 is a rear elevation view thereof;
FIG. 9 is a top view thereof;
FIG. 10 is a bottom view thereof;
FIG. 11 is a side view thereof;
FIG. 12 is a side view thereof;
FIG. 13 is a top, perspective view thereof; the view showing the ramp in a partially open position;
FIG. 14 is a top, perspective view thereof; the view showing the ramp in the open position; and,
FIG. 15 is a top, perspective view thereof; the view showing the ramp in a partially closed position.

The broken lines in the figures illustrate portions of the pet grooming station that form no part of the claimed design.
